(Cl. D57—1)

FIG. 1.

FIG. 2.

FIG. 3.

FIG. 1 is a side elevational view of a temple for spectacle frames embodying our new design.

FIG. 2 is a top plan view thereof.

FIG. 3 is a cross-sectional view taken on line 3—3 of FIG. 1 in the direction of the arrows.

FIG. 4 is an enlarged cross sectional view taken on line 4—4 of FIG. 1 in the direction of the arrows.

FIG. 5 is an enlarged cross sectional view taken on line 5—5 of FIG. 1 in the direction of the arrows.

The characteristic feature of our design for a temple for spectacle frames resides in the generally helical portion thereof, as shown.

We claim:

The ornamental design for a temple for spectacle frames, as shown and described.
